CARBURETOR

Elmer Olson, Rochester, N. Y., assignor to General Motors Corporation, Detroit, Mich., a corporation of Delaware

Application March 8, 1954, Serial No. 414,763

2 Claims. (Cl. 261—65)

This invention relates to carburetors for internal combustion engines, particularly to carburetors for use on automotive vehicles and, more particularly, to means for automatically and variably controlling the flow through the mixture passage in response to changes in throttle position as well as in response to changes in speed and load while the throttle remains in fixed position.

The invention is designed for use primarily in a compound carburetor in which there is a primary mixture passage which functions under all operating conditions and a secondary mixture passage which functions only after the primary throttle which controls flow through the primary mixture passage has been opened to a predetermined extent. However, it will be understood that the invention is not limited in its use to such a carburetor, but might be employed in a carburetor of conventional design having a single mixture passage.

It is the primary object of the present invention to provide means which will be effective, particularly in a compound carburetor, to prevent admission of sufficient air immediately following a relatively wide opening movement of the throttle, particularly when the engine is operating at relatively low speed, to cause unsatisfactory operation of the engine.

According to the present invention, this object is attained by the provision of an unbalanced suction operated valve in the secondary mixture passage between the main fuel inlet which supplies fuel thereto and the throttle which controls the amount of mixture flowing therefrom into the engine manifold. This valve is normally held closed by a spring or other suitable means which exerts a force tending to move the valve toward closed position and which must be overcome by the effect of suction to effect opening of the valve. The valve, therefore, does not open as rapidly as the throttle and retards the flow through the secondary passage.

If this suction operated valve was not provided and the primary throttle was opened wide enough, at a time when the engine was operating at low speed with the secondary throttle closed, to effect opening of the secondary throttle to any appreciable extent, the mixture would become too lean for proper operation of the engine. The reason for this is obvious. At the time the throttle is opened, no fuel or air is flowing through the secondary mixture and when the throttle therein is opened, there will be a sudden in-rush of air with almost no flow of fuel, due to inertia. This in-rush of air leans the mixture to such an extent that the engine will not function properly, but when the suction operated valve which is the subject of this invention is provided, the opening of the valve with respect to the secondary throttle is retarded sufficiently to substantially eliminate the leaning of the mixture which would otherwise occur, so that the engine will function properly.

It might be supposed that the conventional accelerator pump which is generally provided in carburetors and is operated upon opening movements of the throttle, to provide a proper mixture upon acceleration, would take

2

care of this difficulty, but if a pump was used which is of sufficient capacity to provide a mixture of the desired fuel content when the primary throttle is opened far enough to effect a substantial opening of the secondary throttle, the pump capacity would be too great for lesser openings of the primary throttle and if the latter was opened to increase speed, but not enough to open the secondary throttle, the mixture would be too rich and the engine would function improperly upon acceleration in the lower speed ranges.

As already indicated, the valve which is the subject of the present invention is particularly useful in a compound carburetor for correcting the difficulty previously described but is also useful in a carburetor having a single

15 mixture passage. In such a carburetor, because of the difference in weight of the air and fuel, any opening movement of the throttle effects a quicker increase in flow of air than in flow of fuel and the mixture would momentarily become leaner unless some compensating means is employed. This difficulty is usually overcome by the provision of the conventional throttle operated accelerator pump, but if a valve such as disclosed herein is employed, a pump of smaller capacity can be used successfully because the valve aids the action of the pump.

20 Likewise, in any carburetor, whether a single outlet device or compound carburetor, the provision of a valve such as that which is the subject of this invention, aids in stabilizing the mixture proportions upon changes in speed and load with fixed throttle position. For example,

25 if a vehicle on which a carburetor having the valve disclosed herein is employed, starts downhill, there will be an increase in engine speed due to reduction in load. This will cause an increase in flow through the mixture passages and because of the inertia of the fuel, the amount of air drawn into the manifold will increase faster than the fuel. If a valve such as that disclosed herein is provided, the flow of air will be retarded sufficiently to cause the flow of air and fuel to increase substantially at the same rate and the mixture formed is a more stable one than if the valve

30 was not employed.

An unbalanced flat valve of the butterfly type has a tendency to hang as it approaches its wide open position so that the valve does not open fully. This is due to the fact that as the valve approaches its wide open position, the pressures effective on opposite sides of the valve shaft become so nearly equal that there is insufficient force effective to move the valve further toward its open position. Accordingly, it is one of the more specific objects of the present invention to provide a suction opened 45 valve in the intake passage between the fuel inlet and throttle which normally held in closed position but is opened by suction and which will be opened to its fullest extent when the throttle reaches fully open position.

Further objects and advantages of the present invention will be apparent from the following description, reference being had to the accompanying drawings wherein a preferred embodiment of the present invention is clearly shown.

In the drawings:

50 Figure 1 is a side elevation of a compound carburetor embodying the present invention and cut away to show some parts in section on the line 1—1 of Figure 2;

Figure 2 is a bottom plan view of the device of Figure 1;

55 Figure 3 is a fragmentary section on the line 3—3 of Figure 1; and

Figure 4 is a view similar to Fig. 3 showing a modified form of the invention.

In the drawings, the invention is shown as incorporated 60 in a compound carburetor of the type shown in applicant's copending application S. N. 264,136, filed December 29, 1952, in which there are four entirely separate mixture

passages each of which has a separate outlet which connects with a separate passage in the intake manifold. The detailed construction of this carburetor is not in any way material so far as the present invention is concerned and for this reason, only the outline of the carburetor and the general arrangement of two of the mixture passages are shown in the drawings.

As shown, the carburetor comprises three separate castings, 2, 4 and 6 which are secured together in any suitable way and when assembled, four mixture passages, in each of which a combustible mixture of air and fuel is formed, extend through the castings and when the carburetor is positioned on the manifold, are in registry with four passages that are formed in such manifold and convey the mixture formed in the carburetor to the engine intake ports.

The casting 2 is an air inlet casting and air enters inlet ports at the top and flows into mixing chambers which are formed in the casting 4. There are four of these mixing chambers, two of which are primary mixing chambers which function at all engine speeds and all throttle positions and the other two are secondary mixing chambers which are brought into action to supply additional mixture only in the upper part of the speed range, for example, speeds above 40 or 50 miles per hour. In Fig. 1 the two secondary mixing chambers 8 and 10 are shown. The casting 6 is the outlet casting and this casting is adapted to be secured in the usual way to the engine intake manifold, being provided with an attaching flange 12, as best shown in Fig. 2 for this purpose. This flange has holes 14 through which attaching bolts extend when the carburetor is assembled in operative position.

Secured to a primary throttle shaft 16 suitably journaled in the casting 6 are two primary throttles 18 and 20, while secured to a secondary throttle shaft 22, also rotatably journaled in casting 6 are two secondary throttles 24 and 26. The primary throttles control the quantity of mixture supplied to the manifold through outlets 28 and 30 which are supplied with a mixture of fuel and air by primary mixing chambers associated therewith, while the secondary throttles control similar outlet passages 32 and 34 which are supplied with combustible mixture by secondary mixing chambers 8 and 10 which are of the construction shown in Fig. 2. The primary throttle shaft 16 is operated by a manually actuated operating connection which is connected thereto and there is an operating connection between shafts 16 and 22 which is so constructed that the shaft 22 is not moved until shaft 16 has made a predetermined movement toward open throttle position. This mechanism is not shown herein because its specific construction is of no moment so far as the present invention is concerned, but such mechanism may be of the same construction as shown in application S. N. 264,136.

All of the mixing chambers, both primary and secondary, are of similar construction and in each there is a primary venturi tube, such tubes being designated 40, and each of these tubes discharges into a large venturi tube 42. The tubes 40 are each supported by a tubular arm, as shown in the above application, which has a bore that conveys a rich mixture of fuel and air which is introduced into the tube 40 through orifice 41, while the larger tubes 42 are integral with the casting 4 and form the wall of each mixing chamber. Primary and secondary fuel chambers are formed in the casting 4, the secondary chamber being indicated at 44 and supplying fuel to the two secondary mixing chambers 8 and 10 while the primary fuel chamber, which is not shown, supplies fuel to the two primary mixing chambers in the same way as fuel is supplied to the secondary mixing chambers 8 and 10.

All of the mechanism so far described is disclosed in the earlier application above referred to and now, the mechanism which has been added to such device according to the present invention, will be described. In each of the secondary mixing chambers 8 and 10 a suction

operated valve has been provided between the discharge end of the venturi tube 40 and the bottom of the casting 4 so that such valves are positioned between the venturi tubes 40 and the secondary throttles 24 and 26. There are two forms of the invention disclosed and in each the function is substantially the same and the suction operated valve is supported for rotation in a cylindrical insert which is press-fitted or otherwise supported in a recess formed in the wall of the secondary mixing chamber at the lower end thereof, adjacent the bottom of casting 4.

As disclosed in Fig. 3, the outlet end of the mixing chamber shown therein is enlarged as indicated at 50 and fitted in this enlargement is a cylindrical insert 52 of such width that when seated against the shoulder 54, the lower edge of such insert terminates flush with the bottom of casting 4 and engages the gasket 56 which separates the castings 4 and 6. A short shaft 58 is rotatably mounted in this insert 52 and secured to this shaft by screws 60 is a valve 62 which is normally held in a position where one edge of the valve engages a pin 64 which is press fitted in an opening 66 in the wall of the insert and the inner end of which extends for a very short distance into the mixing chamber, as shown in Fig. 3.

To move the valve to this position, an arm 68 has an offset extension 70 through which a screw extends, so that extension 70 is clamped between the screw and the valve 62. Secured in the other end of arm 68, in any suitable way, is a pin 72. This pin is engaged by a loop formed in one end 74 of a spring which has a coiled portion 76 and another end portion 78 which is looped around a pin 80 mounted in the insert 52 and extending across a slot 82 formed therein and into which the spring end 78 extends. The spring ends 78 and the center coil 76 of the spring are both received in a slot 84 formed in the large venturi tube 42 and the spring end 74 extends through a slot 86 formed in the wall of the small venturi tube 40. These slots prevent any lateral movement of the spring and maintain it in proper position when the device is assembled. This spring normally holds the valve closed and the valve is progressively opened against the force of such spring as the throttle is opened, the shaft 58 being mounted off-center so that the valve is unbalanced and moves in response to variation in the suction effective thereon.

The valve 62 is not a flat plate, as butterfly valves usually are, but different parts of the valve lie in different planes, which are at angles to each other. This form of valve is provided because, if the valve is a flat plate it has a tendency to hang as it approaches open position and sometimes will fail to reach the fully open position. This is due to the fact that as the valve moves counter-clockwise, upon an increase in the suction effective thereon, it reaches a position so much in line with the path of the entering air that the forces effective on opposite sides of the valve shaft are almost balanced and sometimes the effective force tending to rotate the valve will be insufficient to overcome the forces opposing movement thereof. To overcome this difficulty, the valve 62 has four parts designated A, B, C and D, all of which lie in different planes. During the first part of the opening movement of the valve the effect of suction on the part D opposes opening of the valve, but due to the angularity of such part D, as the valve approaches open position, the top of such part passes the center line of the shaft 58 so that the effect of suction on such part also tends to open the valve, aiding the effect of suction on the part A, so that the valve will be carried to full open position. The position of the part D as the valve approaches open position is indicated in dotted lines in Fig. 3 and the effect of suction on such part will be clearly apparent.

The construction shown in Fig. 4 is substantially the same as that of Fig. 3 except for the fact that the spring means which holds the valve closed and opposes opening movement of the valve is somewhat different. A spring

96 has one end connected to a tang 98 punched out of the valve and the other end connected in a hole 100 formed in a lug 102 which is secured in position on the inner wall of the insert 52 by a screw 104, or in any other suitable way.

The spring arrangement is such that the force exerted thereby in opposition to opening movement of the valve does not increase as much per unit of movement of the valve when the valve approaches open position as when the valve starts to move. This is to compensate for the reduction in effective suction as the valve moves toward open position and to bring about movement of the valve at a reasonably uniform rate during its whole range of movement.

The operation of the valve is apparent. When the throttle is opened to increase the speed of the engine the suction effective on the valve 62 is, of course, increased and the valve will open in response thereto. However, the opening of the valve, being opposed by the spring which is effective thereon, is somewhat retarded and a sudden increase in air flow as compared to fuel flow such as would take place if the valve was not provided, is substantially prevented and a rich enough mixture is maintained for proper acceleration. Also, if there is an increase in suction at points anterior to the throttle, due to a change in speed while the throttle is in fixed position, as would take place upon reduction in load due to descent of an incline, the provision of the valve 60 tends to stabilize the mixture proportions and prevent such fluctuations therein as would bring about unsatisfactory operation.

It will be understood that there are similar suction operated valves in each of the secondary mixture passages but such valves are not provided in either of the primary mixture passages as they are not necessary therein. Also, while the invention is shown as embodied in a four-outlet carburetor having two primary mixture passages and two secondary mixture passages, the invention is applicable to a dual carburetor in which there is only one primary and one secondary mixture passage, and also to a single outlet carburetor, as it is also desirable to retard the admission of air to the mixture

passages of such carburetors upon acceleration. By temporarily restricting the air flow the effect of the conventional accelerator pump is augmented so that a pump of less capacity can be employed and a mixture of proper proportions more easily obtained.

While the embodiments of the present invention as herein disclosed constitute preferred forms, it is to be understood that other forms might be adopted.

What is claimed is as follows:

1. In a carburetor, a mixture passage having a mixture chamber formed therein, means for introducing fuel and air into said mixing chamber to form a combustible mixture thereof, a throttle valve posterior to the mixing chamber and controlling the flow of mixture therefrom, an annular recess formed in the wall of the mixture passage adjacent the outlet end of the mixing chamber, a sleeve positioned in said recess and having the same internal diameter as that of the mixture passage adjacent thereto, a shaft rotatably supported in said sleeve and terminating within said recess a suction operated valve fixed to said shaft for controlling flow through the mixing chamber rotatably supported in said sleeve, a spring means also supported on said sleeve and connected to said last-named valve so as to normally hold the valve in closed position, said spring being disposed in said mixing chamber.
2. A carburetor as defined in claim 1 in which said valve includes an anteriorly projecting arm and further in which said spring means comprises a single spring element disposed anteriorly of said valve and fixed at one end to said sleeve and at the other end to said arm.
